UNITED STATES PATENT OFFICE

2,057,412

APPARATUS FOR EYE TESTING

Arthur L. Boyd, Brockton, Mass.

Application December 15, 1934, Serial No. 757,677

1 Claim. (Cl. 88—20)

My present invention is a novel and improved method of and apparatus for facilitating certain well-known and standard methods of eye testing, and is particularly directed to improve and perfect such devices and methods, as well also to combine in one card or device both the usual test types and devices for effecting the phoria test.

Heretofore it has been necessary for separate and distinct operations to be carried out, with separate apparatus for optometrists to test a patient's eyesight with test types of varying grades and distances, and then to have a separate phoria test for concentration of the patient's eyesight.

By my present invention, I prepare a card with the usual test types thereon and associated therewith, preferably centrally of the card, I provide a standard scale to cooperate with a light to effect the phoria test.

Furthermore, I utilize a simple pocket flashlight holder, with proper reflecting means, and means to attach the same to the test type card in proper alignment so that the entire apparatus can be instantly assembled, ready for use, and with a minimum of expense.

Furthermore, my invention enables the printed cards prepared for both the combined test type and phoria test to be supplied and shipped at considerable distance at a minimum of expense. The operator can purchase a supply of the hand flashlights and can renew the batteries therefor from time to time, as desired, at any ten cent store throughout the country.

Heretofore, expensive apparatus has been necessary to perform the phoria test and this expense, cumbersomeness, and space required have rendered it extremely limited in use and difficult for the average optometrist, or those practicing in small towns, to have the advantage of same, whereas my device, being simple, compact, and effective, and manufactured at a nominal cost, is capable of universal use, thus greatly increasing the advantages of the phoria test in describing corrective lenses for the patient needing the same.

Referring to the drawing showing preferred embodiments of my invention,

Fig. 1 is a plan view of my combined card for test types and phoria test with the portable flashlight attached thereto;

Fig. 2 is a side view of the same;

Fig. 3 is an enlarged view of the reflecting attachment which I apply to the flashlight and with the aligning and attaching means;

Fig. 4 is a cross-sectional view, and

Fig. 5 is a fragmentary cross-sectional view showing a modified form of the illuminating feature.

As shown in the drawing, I prepare a card 1 printed with a suitable series of test types 2, 3, 4, 5, 6, and 7 designating diagrammatically all varying grades and types. At any suitable place in the card 1, I supply the scale 10 for the phoria test with a central recess 12, through which a light may shine. Also, on the card 10 I prefer to supply a metallic reinforcement 14 bent about the lower end of the card 1 and fixed centrally thereto to receive and hold a spring clip 15 of the pocket flashlight holder 16. Attached to the upper part of the holder 16 is a spring clip 18 having an angularly positioned reflecting member 20 on the inner side of which is a reflecting plate or surface 21. This may be secured in any suitable manner and, preferably, is a chromium plate zinc sheet secured to the inner surface of the angularly positioned portion 20 by a series of side clips 22, stamped out of the side wings 23 of the reflecting holder portion 20. The pocket flashlight 16, holder 20, and reflector 21 are suitably proportioned relatively with the opening 12 through the test card 1, so that the reflector 20 will be in alignment with the opening 12 when the holder 16 is attached to the card by the clip 15 engaging the plate 14 at the bottom of the card 1.

In order to hold the card 1 and flashlight holder 16 in correct alignment and insure reflection from the light 25 through the opening 12, I provide on the back of the holder 20 a pair of clips 26, 28 through which a pin 30 is secured and forced through the card 1 directly above the opening 12, as clearly shown in Figs. 1, 2, and 3. This insures correct alignment of the holder and card during use.

While I find it advantageous and convenient to provide the attachment comprising the spring clip 18 and the holder 20 positioned at 45° relatively with the holder 16 and card 1 to produce the reflection from the light 25 through the opening 12, I may also provide a small recess 31 through the sides of the holder 16 in a position to permit the light from the lamp 25 to shine directly therethrough and to have the same proportioned with the opening 12 so that the opening 21 will register with the opening 12 in the card 1. This would eliminate the necessity of the attaching clip 18 and reflector 21.

This modification simplifies the construction but necessitates a special opening 31 to be formed in the sides of the holder 16. In either form, the resultant effect and advantage is the same, and

various other modifications will readily occur to those skilled in the art, and which modifications are within the scope of my present invention.

- In using the apparatus it is customary to carry
- 5 a set or number of the testing charts, which may be readily contained in an envelope in the pocket of the optician, with one or more of the flashlight elements 16 also being carried in the pocket, being held in the pocket by clip 15, and ready for
  - 10 instant use. The chart and member 16 are instantly assembled by fitting the same in position and in proper alignment with the pin 30 so that the reflector 21 will register with the opening 12, whereupon the phoria test is performed.
  - 15 This consists in first using a red colored lens, which will thereupon show the exphoria or esophoria, at either right or left, respectively, of the center opening, and the same may be measured on the scale 10 in alignment with the opening 12. Thereupon a displacement prism is utilized, which will show the same result only above or below the opening 12, no scale being necessary in the latter instance. Due corrections in accordance therewith are thereupon made.
  - 20

The advantages, usefulness, importance, and desirability of my invention combining in a simple, efficient, and inexpensive manner both the phoria test and type test for use with an inexpensive, detachable, and readily renewable light 5 element will be readily appreciated, and I wish to claim these features and the method of simultaneous testing herein broadly.

I claim:

An improved article of manufacture comprising- 10 a pocket flashlight member provided with a resilient clip adjacent the lamp, a reflector on the clip angularly positioned above the lamp and having a pin mounted on the back of the reflector adapted to penetrate and hold a test chart with 15 an aperture therein for phoria tests, a holder on the flashlight near the end opposite to said lamp and positioned to hold the test card with the opening therethrough in alignment with the reflector and with said pin penetrating said card 20 above said opening, both holder and pin providing detachable means for connecting the card and flashlight in a proper alinement.

ARTHUR L. BOYD.
